LOOSE LEAF BINDER

Adolph G. Lotter, Milwaukee, Wis., assignor to Stationers Loose Leaf Company, Milwaukee, Wis., a corporation of Wisconsin

Application February 17, 1958, Serial No. 715,687

2 Claims. (Cl. 129—8)

This invention relates to loose leaf binders, and has as its purpose the provision of a loose leaf binder having improved releasable sheet retaining means of unusually simple construction which not only provides for the transfer of binder sheets from one stack in the binder to another but greatly facilitates access to any of the binder sheets.

More specifically, it is a purpose of this invention to provide a loose leaf binder of the character described with a sheet retaining unit comprised of cooperating relatively movable sections, each having binder posts thereon, and one of which sections is movable from a normal sheet retaining position cooperating with a binder posts of the other section when the binder is closed to retain sheets in an orderly stack within the binder, to an inverted transfer position alongside the other section when the binder is open to dispose its binder posts in upright positions laterally adjacent to those of the other section so that single sheets or groups of adjacent sheets impaled on the binder posts of said other section may be removed therefrom and transferred to the posts on the movable section. Moreover, this construction makes any sheet of the stack in the binder readily accessible by providing for shifting of the group of sheets thereabove along with the movable section of the sheet retaining unit to its transfer position.

A further object of this invention resides in the provision of a loose leaf binder of the character described, which incorporates means for releasably connecting said sheet retaining sections with one another through the back of the closed binder, so as to normally preclude motion of said movable sheet retaining section out of its normal sheet retaining position.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention constructed according to the best modes so far devised for the practical application of the principles thereof and in which:

Figure 1 is a fragmentary perspective view of a loose leaf binder embodying the principles of this invention, showing the binder with its covers open;

Figure 2 is a cross sectional view through the binder taken along the plane of the line 2—2 in Figure 1 but showing the binder with its covers closed;

Figure 3 is an end elevational view of the binder shown in Figures 1 and 2, illustrating the sectional construction of the sheet retaining means and showing one of the sections thereof lifted out of its normal sheet retaining position;

Figure 4 is a view similar to Figure 3 but illustrating

2

the movable sheet retaining section shifted to an uppermost position and partly swung toward a transfer position;

Figure 5 is a fragmentary perspective view of the sheet retaining means, showing the sections thereof in their transfer positions;

Figure 6 is a sectional view through the binder, showing the same with its covers open, and with the sheet retaining sections in their transfer positions seen in Figure 5;

Figure 7 is a perspective view similar to Figure 1 but illustrating another embodiment of the invention;

Figure 8 is a fragmentary perspective view showing the sheet retaining sections of Figure 7 in their transfer positions; and

Figure 9 is a fragmentary perspective view of still another embodiment of the invention.

Referring now more particularly to the accompanying drawings in which like reference characters have been applied to like parts throughout the several views, the numeral 10 generally designates a loose leaf binder having a rigid cover comprising a back section 11, top and bottom cover sections 12 and 13, respectively, and substantially narrow top and bottom hinge strips 14 and 15, respectively, by which the covers are hingedly connected to the back section. The sheet retaining unit of this invention, generally designated 17, is secured to the inner face of the bottom hinge strip 15 by rivets 18. Its purpose is to releasably hold a stack 35 of sheets in orderly fashion within the binder, and a latch mechanism 19 permanently secured to the inner face of the top hinge strip 14 by rivets 20, and normally cooperating with a portion of the sheet retaining unit, must be actuated to effect release of the sheets from the binder.

The sheet retaining unit 17 comprises two relatively movable frame sections, a stationary lower frame section of U-shape, generally designated 21, and a movable upper frame section of inverted U-shape, generally designated 22. The U-shaped lower frame section has an elongated

straight bight 23 of slightly less length than the bottom hinge strip 15, and it is flatwise secured thereto by the rivets 18 hereinbefore described. It also includes opposite legs 24 projecting vertically upwardly from the ends of the bight 23, and three binder posts which are fixed to the bight 23 and project vertically upwardly therefrom. The center post 26 is solid, but the two end posts 27 are of tubular construction. These posts, of course, are arranged in a row lengthwise of the bight 23, and while the tubular end posts 27 may have a length substantially equal to that of the legs 24, the center post 26 is slightly shorter.

The movable upper frame section, as stated, is of inverted U-shape. Its bight 29 normally extends lengthwise across the space between the upper ends of the legs 24 of the lower frame, parallel to the bight of the lower frame, and its opposite legs 30 project vertically downwardly toward the bight 23 of the lower frame and each loosely overlaps the entire length of one of the legs 24 of the lower frame. This disposes the ends of the legs 30 substantially directly adjacent to the ends of the bight 23 of the lower frame.

The upper frame section 22 is also provided with three binder posts, fixed to the bight 29 of the upper frame, and projecting downwardly toward the bight of the lower frame. As shown best in Figure 2, the two

end posts 32 are solid and are normally telescoped for substantially their entire length into the tubular end posts 27 of the lower frame 21. The center post 33 of the upper frame, however, is of tubular construction and is telescoped over the solid post 26 of the lower frame.

According to this invention the two frames 21 and 22 comprising the upper and lower sections of the sheet

retaining unit are connected in a unique manner which provides for lifting the upper frame 22 out of its normal, sheet retaining position seen in Figures 1 and 2, with its binder posts in full telescoping relation with those of the lower frame, to an uppermost position at which its binder posts are above those on the lower frame section. The connection between the two frames further provides for pivotal motion of the upper frame 22 relative to the lower frame from its uppermost position to a transfer position such as shown in Figures 5 and 6, disposed alongside the lower frame 21 and in which transfer position the binder posts of both frames project upwardly but are disposed in separate spaced apart rows.

This connection between the two frames comprises a pair of coaxial pins 37 fixed to the upper end portions of the legs 24 on the lower frame 21 and projecting outwardly from the exteriors of the legs, to terminate in enlarged heads 38 spaced a distance from the legs 24 corresponding to the thickness of the legs 30 of the upper frame 22. These pins normally project through the upper portions of elongated slots 39 in the legs 30 of the upper frame, and these slots extend for substantially the entire length of the legs, or a distance at least equal to the length of the binder posts on the movable frame 22. The enlarged heads 38 on the pins 37 engage over portions of the legs 30 adjacent to the slots 39 to thus preclude displacement of the upper frame from the lower frame, and the engagement of the pins in the upper and lower ends of the slots defines the normal sheet retaining position of the upper frame, and its uppermost position, respectively.

It is an important feature of the construction shown in Figures 1 through 8 that the upper frame is constrained to up and down translatory movement relative to the lower frame except when it is in its uppermost position, and that as soon as it is swung away from its uppermost position, sliding thereof lengthwise of the slots in its legs is positively precluded. For these reasons, each of the enlarged heads 38 on the pins 37 has a flat 40 formed on one side thereof, to flatwise engage the opposing surface of an outwardly projecting flange 41 secured to each leg 30 along one edge of the slot 39 therein. Inasmuch as the flanges 41 terminate a slight distance upwardly from the lower ends of the slots 39 in the legs 30, the flats on the heads 38 of the pins prevent all but upward translating motion of the frame 22 out of its normal sheet retaining position, until the frame 22 reaches its uppermost position at which the flats on the heads 38 of the pins clear the flat sides of the flanges 41 and the adjacent ends of the flanges are contiguous to the circular peripheral portions of the heads. At this time, of course, the binder posts on the movable frame are free of those on the stationary frame, and the upper frame is no longer constrained to an attitude with its legs lengthwise aligning with the legs 24 of the lower frame. Consequently the engagement of the pins 37 in the lower ends of the slots 39 provides a pivotal connection between the frames enabling the upper frame to be swung counterclockwise as viewed in Figures 4, 5 and 6, about the common axis of the pins 37, to an inverted transfer position with its bight lengthwise adjacent to the bight 23 of the lower frame and its binder posts extending upwardly in spaced side by side relation to the cooperating binder posts on the lower frame. During all such pivotal motion of the movable frame the rounded peripheries of the heads 38 on the pivot pins are engageable by the adjacent ends of the flanges 41, as seen in Figure 4, to prevent relative sliding movement between the frames.

It should be borne in mind, however, that the slots 39 in the legs 30 of the upper frame must be long enough to enable complete disengagement between the telescoped binder posts. Consequently, the binder posts of the lower frame do not interfere with swinging of the upper frame to its transfer position seen in Figure 5. The sheets of

the stack 35 may thus remain impaled solely upon the upright posts 26 and 27 of the lower frame to be transferred one by one or group by group to the upright posts on the now inverted movable frame, as seen in Figure 6, or any desired group of sheets may be removed from the top of the stack with the upper frame during such shifting thereof to its transfer position to quickly provide access to any sheet of the stack.

This greatly facilitates work upon any desired sheets of the stack, and its is further advantageous in that it allows an upper part of the stack to be held neatly and in proper arrangement by its impalement on the posts of the movable frame until work is completed upon the various sheets of the binder. Thereafter the sheets need not be removed from the posts 32 and 33 of the movable frame and reimpaled upon the posts of the stationary lower frame 21 before the movable frame section 22 is swung clockwise to realign its legs with those of the lower frame and lowered to its sheet retaining position seen in Figures 1 and 2, but they can be held on the movable frame section while it is shifted back to its normal position seen in Figures 1 and 2.

It is a further feature of this invention that the upper or movable frame 22 can be releasably locked in its lowered, sheet retaining position seen in Figures 1 and 2, by the latching mechanism 19 carried by the top hinge strip 14 when the top cover is closed over the stack of sheets 35, see Figure 2. For this purpose, locking pins 46 are fixed to the bight 29 of the movable frame, near its opposite ends, and project upwardly a short distance therefrom. These pins have rounded outer ends 47, and each has a circumferential groove 48 therein. A dowel or locating pin 49 is also fixed to the bight 29 of the movable frame, and it projects upwardly therefrom at a location intermediate the locking pins 46.

The latch mechanism 19 directly overlies the bight 29 of the upper or movable frame 22 when the top cover is closed, as in Figure 2. It comprises a tubular guide 51 fixed to the inside of the top hinge strip 14, having a latch bar 52 received therein for endwise motion lengthwise of the back section 11 and the bight of the upper frame. A tension spring 53 connected between the tubular guide 51 and the latch bar 52 tends to yieldingly hold the latch bar in an operative locking position with one end projected from the adjacent end of the guide, but enables it to be slid endwise to an inoperative or unlatching position upon depression of a finger piece 54 on said projecting end of the latch bar.

In the closed and latched position of the binder seen in Figure 2, the locating pin 49 projects upwardly through a cooperating locating hole 55 in the tubular guide and into a slot 56 in the latch bar 52 which allows the bar to be shifted endwise without interference from the locating pin. The locking pins 46 project upwardly through suitable holes 57 in the tubular guide, and into bean-slots 58 in the latch bar, at one end of the slots, and the tension spring 53 releasably holds the latch bar in an operative or locking position at which said ends of the bean slots engage and bottom in the circumferential grooves 48 in the locking pins. This prevents the latching mechanism from being lifted off the upper frame except upon depression of the finger piece 54 on the projecting end of the bar, to disengage the bar from the grooves 48 in the locking pins. In the closed and latched position of the binder as seen in Figure 2, therefore, the cooperating frames may be considered as connected together by the back section 11 and the two hinge strips, to be held thereby against all movement relative to one another, it being understood that the back section 11 then occupies an upright position extending substantially from bight to bight of the two frames 21 and 22.

A stop pin 60 fixed in the tubular guide 51 and engaging in a slot 61 in the latch bar 52 may serve to limit spring-propelled motion of the latch bar when the binder is in its open position seen in Figure 1. The same pin 60,

or alternatively the finger piece 54, may serve to limit endwise motion of the bar in the opposite direction.

When closing the binder, the back section 11 and its connected top cover section 12 are swung upwardly to dispose the top cover over the stack of sheets, from their positions shown in Figure 1. The locating hole 55 in the tubular guide 51 may then be brought into registry with the locating pin or dowel 49 to facilitate registry of the locking pins with the holes 57 in the guide. Thereupon, the top hinge strip 14 is pressed down onto the bight 29 of the upper frame, and the rounded outer ends of the locking pins momentarily cam the latch bar against the spring force acting thereon the slight amount necessary to assure proper entry of the locking pins into the bean slots 58. As soon as the grooves 48 in the locking pins align with the plane of the latch bar, the tension spring snaps the same to its locking position shown in Fig. 2.

If desired, the binder posts on the lower frame 21 of the sheet retaining unit may be made entirely independent of the binder posts on the upper frame 22, as shown in Figure 7. The lower frame thus may have only two posts 26' fixed to its bight 23 and projecting upwardly therefrom in spaced relation to one another, each adjacent to but spaced from one of two similar posts 32' on the upper frame 22. This gives a total of four binder posts to engage in four separate apertures in a stack of sheets 35' in the binder. In this case also all of the binder posts may be of solid construction, and slightly shorter than the length of the slots 39 in the legs 30 of the upper frame 22.

Except for the fact that the flanges 41' in this case are solid reinforcing bars each fixed to one of the legs 30 of the upper frame along one edge of the slot 39 therein, the binder illustrated in Figures 7 and 8 is in all other respects similar to that previously described.

In the modified embodiment of the invention illustrated in Figure 9, the legs 24 of the lower frame 21 are shown overlying the outer sides of the slotted legs 30 on the upper frame. The hinge pins 37' by which the cooperating frame sections are pivotally connected, are likewise fixed in the upper ends of the legs on the lower frame, but they project inwardly through the slots 39 in the legs of the upper frame to terminate in enlarged heads 38' by which disconnection of the two frame sections is prevented. In this case, however, the binder posts of the upper and lower sections are of the telescoping type described in connection with Figures 1 and 2, and this telescoping engagement of the posts is relied upon to constrain the movable frame 22 to vertical translating motion relative to the lower frame when it is lifted to its uppermost position or lowered to its normal position.

From the foregoing description taken together with the accompanying drawings, it will be readily apparent to those skilled in the art that this invention provides an improved loose leaf binder wherein access to all of the sheets in the binder and their temporary transfer from one stack to another is greatly facilitated.

What is claimed as my invention is:

1. In a loose leaf binder, the combination of: an elongated back section, top and bottom covers, and elongated substantially narrow top and bottom hinge strips hingedly connecting the covers to the back section; a sheet retaining unit mounted on the bottom hinge strip, said sheet retaining unit comprising U-shaped upper and lower frames having elongated horizontal bights in spaced parallel relation to one another, each frame having opposite legs extending perpendicularly from its bight substantially to the bight of the other frame with each leg slidably overlapping one of the legs on the other frame,

binder posts connected to the bight of each frame and projecting toward the bight of the other frame, said posts being arranged in a common row lengthwise of said bights, and means at all times connecting the adjacent legs of the frames to provide for lifting of the upper frame relative to the lower frame, the covers and back section, to an uppermost position at which the end portions of said legs are adjacent to one another and the ends of the posts on the upper frame are at a level at least as high as the ends of the posts on the lower frame, said connecting means providing for pivotal motion of the upper frame, the covers and back section, relative to the lower frame out of its uppermost position about an axis parallel to the bight of the lower frame, to an inverted position at one side of the lower frame with the bight of said upper frame lowermost and lengthwise adjacent to the bight of the lower frame to dispose said binder posts in upright positions in spaced side by side rows, thus to enable sheets impaled on the binder posts of the lower frame to be removed therefrom and transferred to the binder posts of the other frame; and latch means for releasably connecting the bight of the upper frame to the inside of the top hinge strip so as to normally prevent lifting of the upper frame toward its uppermost position.

2. In a loose leaf binder, the combination of: an elongated back section; top and bottom covers hingedly connected with the opposite longitudinal edges of the back section; a sheet retaining unit carried by the binder and comprising an elongated lower member on a portion of the bottom cover adjacent to the back section, extending lengthwise thereof, and having upwardly projecting binder posts thereon, a movable elongated upper member normally occupying a sheet retaining position in spaced superimposed relation to the lower member and entirely above all of the posts on the lower member, said upper member having binder posts thereon which project downwardly at locations intermediate posts on the lower member and all of which terminate above the lower member, and means at all times connecting the adjacent ends of said members to provide for upward movement of the upper post carrying member out of its sheet retaining position to a sheet releasing position spaced a maximum distance above the lower member, said connecting means providing for pivotal motion of the upper member relative to the lower member out of said uppermost position thereof, about an axis parallel to the lower member, toward the back section to an inverted position closely lengthwise adjacent to the lower member and at which the posts on both members are upright and disposed in spaced side by side rows so that sheets impaled on the posts of the lower member may be removed therefrom and transferred to the posts of the inverted upper member; means securing the lower member to said portion of the bottom cover; and releasable latch means connecting the upper member to a portion of the top cover adjacent to the back section, when the binder is closed, whereby the back section restrains the upper post carrying member against upward movement out of its sheet retaining position except upon release of said releasable latch means.
